UNITED STATES PATENT OFFICE.

ALEXANDER W. FINLAYSON, OF DETROIT, MICHIGAN.

GRATE FOR FURNACES.

1,249,365.

Specification of Letters Patent. Patented Dec. 11, 1917.

Application filed May 22, 1916. Serial No. 99,034.

To all whom it may concern:

Be it known that I, ALEXANDER W. FINLAYSON, a citizen of the United States, residing at Detroit, in the county of Wayne 5 and State of Michigan, have invented a new and useful Grate for Furnaces, of which the following is a specification.

This invention relates to grates for furnaces, and it consists in the novel features 10 of construction and arrangement of parts as hereinafter set forth and claimed.

The invention has for its object to provide a grate of simple and improved form for use in the fire boxes of boilers, furnaces 15 and the like, in which the bed of the grate is composed of a plurality of hollow cylindrical bars journaled to rotate independently upon transverse supporting rails adjustably and removably mounted in the base 20 of the furnace, which latter is provided with removable caps or closures, through which said rails and bars may be passed to facilitate assembling and permit of removal for repair and replacement.

25 The invention contemplates such a structural arrangement of the grate bars as will render them hollow to permit circulation of air longitudinally therethrough as a means of cooling the bars to prevent warping.

30 These bars, which are assembled in adjacent parallel relation, are provided with a series of longitudinally and circumferentially spaced radially projecting peripheral fins or lugs which form an open grate-like 35 bed for supporting the fuel, and which, when said bar is rotated, serve to agitate the fuel to release and separate the ashes therefrom.

A preferred embodiment of the essential 40 features of the invention is illustrated in the accompanying drawings, in which,

Figure 1 is a plan view of the base of a furnace showing the grate bars mounted therein as in operation.

45 Fig. 2 is a front elevation of the base partly in transverse section, as on dotted line 2-2 of Fig. 1.

Fig. 3 is a central vertical longitudinal section through the base and one of the grate 50 bars, and showing a portion of a crank handle engaged with one end of the bar.

Fig. 4 is a perspective view of the furnace base having the grate bars removed from the supporting rails which are also removably mounted in said base.

55 Fig. 5 is a fragmentary detail of a por-

tion of the base showing one of the supporting rails partially withdrawn through an opening therein.

Fig. 6 is a sectional view through one of 60 the caps for closing the opening in the base through which the rail is removed.

Referring to the parts by the characters of reference marked on the drawings, 1 indicates a rectangular base or ash pan upon 65 which the furnace or heater is mounted. This base consists of flanged side walls 2, to

the ends of which the front end walls 3 and 4 are secured in overlapping engagement by bolts, as at 5. The front wall 3 is provided with an opening 6, the upper portion of 70 which extends upwardly and outwardly through said wall. This opening is closed by a removable plate 7 secured to the wall by bolts as at 8, and formed transversely 75 through this plate is a series of spaced openings 9. (See Fig. 4.) The side walls 2 of the base are provided at opposite ends with openings 10, through which transverse supporting rails 11 are passed into said base. 80

These rails are formed with a series of U-shaped bearing openings 12 in their upper edges, which are spaced to lie in registering alignment with the openings 9 of the front plate 7 when said rails are positioned with- 85

in the base. The ends of the rails 11 are supported in the openings 10 of the side walls 2 by means of hollow outwardly curved caps 13. These caps are formed at 90 their lower ends with an offset depending tongue 14 forming a shoulder 15, the latter of which rests upon the lower edge of the wall of the opening 10, and the former engages the inner face of said wall to anchor the lower ends of the caps against outward 95 movement. The upper ends of the caps are bifurcated, as at 17, and are detachably locked in engagement with the outer faces of the walls 2 by means of lugs 18 which project laterally from said walls through 100 the bifurcated ends of said caps and receive transverse locking pins 19. (See Figs. 2 and 4.) Set screws 20, extended at an incline through the bases of the caps 13, seat at 105 their inner ends against annular surfaces 21 on the ends of the rails 11, and serve to raise and adjust said rails to the required position to align the U-shaped bearing openings 110 therein with the openings of the front plate 7. Mounted to rotate in the bearings of these rails, and extending at their forward ends through the openings in the plate 7, is

a plurality of cylindrical grate bars 22, each of which is provided throughout its body portion extending between the supporting rails with a circular series of longitudinally spaced prongs or lugs 23 which form an open grate-like surface for supporting the fuel. The body portions of the bars are cored out to form a passage 24 therein and the end portions, which serve as trunnions upon which the bars rotate in the bearings of the supporting rails, are cored out to form reduced passages 25 and 26 communicating with the passage 24 to provide for the circulation of air longitudinally through the bars. The forward ends of the bars extending through the front plate 7 are formed with angular peripheral surfaces 27 to provide a wrench hold for reception in the socket 28 of a crank handle 29 (see Figs. 2 and 3), by means of which said bars may be rotated independently to agitate the fuel and release the ashes therefrom into the base of the furnace.

By this construction of the bars and means for mounting them in the base of the furnace, the grate is formed of a plurality of units, which may be readily inserted for assembling or withdrawn singly or collectively for repair or replacement, and through the

provision of the radially projecting lugs 30 upon which the fuel and fire are supported, together with the rotatability of the bars, the entire circumferential area of the bar is rendered available for service at intervals by rolling the bar so as to present an unused surface when the exposed surface has become worn or damaged by the fire, while the hollow formation of the bar permitting the circulation of air therethrough tends to keep down the temperature in the body of the bar to prevent warping from overheating and thus to enhance the life of the bar and the effective service of the grate.

I claim:—

In a grate, the combination of a base having aligned openings in opposite walls thereof, removable caps for closing said openings, transverse supporting rails adjustably mounted at opposite ends in said caps and removable therewith through said openings, and a plurality of grate bars rotatably and removably mounted in said rails and extending at their forward ends through said base.

In testimony whereof, I sign this specification.

ALEXANDER W. FINLAYSON.
